UNITED STATES PATENT OFFICE.

GEORGE ARTHUR MICKELSON, OF VANCOUVER, BRITISH COLUMBIA, CANADA,
ASSIGNOR OF ONE-HALF TO JAMES MCLAGAN MITCHELL, OF VANCOUVER,
BRITISH COLUMBIA, CANADA.

MARINE TRANSFER APPARATUS.

Application filed March 31, 1921. Serial No. 457,316.

To all whom it may concern:

Be it known that I, GEORGE ARTHUR MICKELSON, a citizen of the United States, and a resident of the city of Vancouver, in the Province of British Columbia, Canada, have invented certain new and useful Improvements in Marine Transfer Apparatus, of which the following is a specification.

My invention relates to improvements in marine transfer apparatus, and the object of my invention is to provide an apparatus of this nature which has a wide range of utility and which is capable of being employed with great facility in the unloading of cargoes carried in barges, scows, or other vessels, enabling such work to be carried out expeditiously and with great convenience so that discharging and transferring operations are effected with the maximum economy and efficiency.

I attain this object by the construction illustrated in the accompanying drawings in which—

Fig. 1 is a side elevation of the apparatus. Fig. 2 is a sectional end view taken through the line 2—2 of Fig. 1 showing method of transferring cargo from a scow or barge.

Fig. 3 is an end view showing method of discharging on to wharf.

Fig. 4 is a detail view of the hinge construction at the lower end of the elevating conveyor.

Figs. 5 and 6 are detail views showing method of detachably connecting the transverse conveyor.

Similar figures of reference indicate similar parts throughout the several views.

1 indicates a floating structure, of scow formation, on which are erected towards each end bridge like structures, indicated generally by the numerals 2 and 3, consisting of braced side columns 4—5 and 6—7 respectively connected together at their upper ends by longitudinal members 8 and 9 and transverse members 10 and 11, and pivotally connected at their lower ends to suitable brackets 12 secured to the columns 4—5 and 6—7 are booms 13 the upper ends of which are maintained in any position to which they may be raised or lowered by lines or falls 14. 15 indicates a donkey engine and 16 a boiler therefor, while 17 indicates a suitably mounted shaft provided with a bevel gear 18

meshing with a bevel gear 19 secured to a vertical shaft 20, and which shaft is rotated by the gear 19.

The shaft 20 is square and extends upwardly the full height of the structure, being rotatably supported at its upper end by any suitable means, and it passes freely through a block 21 capable of being raised or lowered by means of a cable 22, one end of the cable being secured to the block while its free end is passed over a sheave 23 and carried to the donkey engine 15. Vertically slideable on the shaft 20 and rotatably connected thereto by a sliding key is a bevel gear 24 which meshes with a gear 25 secured to the head end shaft of an inclined conveyor 26 arranged longitudinally of the structure 1 and the gear 24 is supported on the block 21 so that lowering or raising the block also lowers or raises the gear 24, maintains both gears 24 and 25 in mesh, and also lowers or raises the head end of the conveyor 26 when required.

27 indicates a cross conveyor the head end of which is supported on a vertically movable block 28 in a position to receive discharge of material from the conveyor 26, and the block 28 may be raised or lowered to raise or lower the head end of the conveyor 27 by means of a cable one end of which is secured to the block while its opposite end is led to the engine 15. The length of the conveyor 27 is such that it can extend on to a wharf, indicated by the numeral 28^a, when the structure 1 is brought alongside same, its outer end being preferably supported on a roller 29, and for the manipulation of this conveyor booms 30 are provided, these booms being pivotally connected at their lower ends to the side columns 5 and suitably guyed at their upper ends so that they may be used for other purposes besides the manipulation of the conveyor.

The lower end of the conveyor 26 is supported on the deck of the scow 1 towards the end thereof and connected to it by a link arrangement, indicated by the numeral 31, is the head end of a longitudinal outwardly extending conveyor 32 the tail end of which is supported by means of suitable tackle 33 hung from the upper end of a boom 34 pivotally connected at its lower end to the side column 6, the tackle being operated as re-

quired by the engine 15. Both the head end of the conveyor 32 and the lower end of the conveyor 26 are also connected to a tackle 35 which passes over a sheave 36 and is led to the engine 15 so that they may be raised or lowered at will and by means of the link arrangement 31 the head end of the conveyor 32 may be raised and carried forward on to the lower end of conveyor 26, as indicated by the dotted lines in Fig. 4, as when discharging bulk cargo, and thus prevent the material dropping between the ends of the conveyors, as might occur if they were then in the position shown by the full lines in Fig. 4. The link 31 is extended on the opposite side of its fulcrum point 37 to form an extension 38 adapted to co-operate with a pin 39 carried by the conveyor 26 and hold conveyor 32 against movement longitudinally from its operative position, as shown in Fig. 4.

The conveyor 32 is driven at its head end by means of a sprocket 40 connected by a chain 45 to a sprocket 46 mounted on the lower shaft of conveyor 26, the operation of this conveyor rotating the sprockets and on the head end shaft 47 of the conveyor 32 is secured a bevel gear 48 which meshes with a bevel gear 49 secured to a shaft 50 extending longitudinally along one side of the conveyor, being carried by suitable bearings 51, this shaft being provided at designated intervals with gears 52, rotatable with the shaft but connected thereto by sliding keys 35 so that they may be moved longitudinally of the shaft to any desired position.

53 indicates a conveyor adapted to extend at right angles to the conveyor 32 and supported at its head end on the shaft 50 at a height suitable for discharging thereonto by arms 54 and 55 the lower ends of which are forked as at 56 to straddle the shaft, from which it will be seen that the conveyor 53 may be placed in any desired position longitudinally of the conveyor 32, and, being provided on its head end shaft with a gear 57 adapted to engage any of the gears 52 when so placed, it is thus capable of being operated by the shaft 50. The tail end of the conveyor 53 may be moved at will by means of the adjacent booms already mentioned and it is supported when in operative position when used in discharging say, a scow, as indicated by the numeral 58 in Fig. 2, by a suitably mounted roller 59, which rests on the deck of the scow.

Intermediate the length of the structure 1 and to one side of the conveyor 26 is erected a vertical framework, indicated generally by the numeral 60, and consisting of four corner posts between which an elevator cage 61 is vertically movable, being raised and lowered by means of a rope 62 led to the engine 15, the posts being provided at 65 their lower ends with wheels 63 mounted on

rails 64 so that the framework 60 may be moved to and fro as required. Each post is provided with a plurality of holes 65 spaced equidistant vertically so that bars 66 may be supported between the posts parallel with the sides of the structure 1, these bars being used to support the ends of gangplanks 67 laid from the barge or scow being discharged to the structure 1 and from the structure 1 to the wharf so that by placing 75 a bar in a pair of lower holes and one in a pair of the uppermost holes and supporting the inboard ends of the respective gangplanks thereon material may be wheeled on the lower plank to the cage, raised thereby, 80 and then wheeled along the upper plank onto the wharf.

The manner in which the apparatus is used and its utility will be obvious as it will be seen that by mooring the scow 1 alongside the wharf, the conveyors 32 and 53, either singly as shown, or in any multiple thereof, may be used with great facility to receive material from adjacent scows, barges, or other vessels, either end on to the 90 scow 1 or alongside of it and convey it on to the inclined conveyor 26 which in turn raises it and delivers it on to the conveyor 27 so that it is thus transferred with great facility and economy from the cargo vessel 95 to the wharf while by providing for the raising or lowering of the conveyors 26 and 27 cargo can be worked at any stage of the tide.

What I claim as my invention is:

1. A marine transfer apparatus comprising, a floating structure, an inclined conveyor mounted longitudinally thereon having its tail end close to the deck of the structure and its head end elevated to above 105 a wharf level, a transverse conveyor one end of which is adapted to be supported on said wharf, its opposite end being arranged to receive material discharged from the head end of the longitudinal conveyor, and means 110 for varying the inclination of said inclined conveyor, said means comprising a vertically movable support on which the head end of said conveyor is carried, and a cable connected at one end to said support and 115 at its opposite end to a power machine.

2. A marine transfer apparatus comprising, a floating structure, an inclined conveyor mounted longitudinally thereon having its tail end close to the deck of the structure and its head end elevated to above 120 a wharf level, a transverse conveyor one end of which is adapted to be supported on said wharf, its opposite end being arranged to receive material discharged from the head end of the longitudinal conveyor, means for 125 varying the inclination of said inclined conveyor, a vertically movable block on which the head end of said conveyor is carried, a vertical rotatable shaft extending freely 130

- through said block, a gear on the conveyor head end shaft, a bevel gear rotatably connected to said vertical shaft vertically slideable thereon and meshing with the said head 5 end shaft gear, said bevel gear being supported on said block, and a cable connected at one end to said block and at its opposite end to a power machine.
3. A marine transfer apparatus comprising, a floating structure, an inclined conveyor mounted longitudinally thereon having its tail end close to the deck of the structure and its head end elevated to above a wharf level, a substantially horizontal 10 conveyor the head end of which is link-connected to the tail end of the inclined conveyor, its tail end extending outboard from the structure, and means for carrying up the said tail end.
- 20 4. A marine transfer apparatus comprising, a floating structure, an inclined conveyor mounted longitudinally thereon having its tail end close to the deck of the structure and its head end elevated to above 25 a wharf level, a substantially horizontal conveyor extending outboard from the structure the head end of which is link-connected to the tail end of the inclined conveyor whereby it may be superposed thereon, a 30 shaft rotatably mounted on one side of said horizontal conveyor and extending longitudinally of the same, and a gear rotatably connected to said shaft slidably mounted thereon.
- 35 5. A marine transfer apparatus comprising, a floating structure, an inclined conveyor mounted longitudinally thereon having its tail end close to the deck of the structure and its head end elevated to above
- a wharf level, a substantially horizontal 40 conveyor extending outboard from the structure the head end of which is link-connected to the tail end of the inclined conveyor whereby it may be superposed thereon, a 45 shaft rotatably mounted on one side of said horizontal conveyor and extending longitudinally of the same, a gear rotatably connected to said shaft slidably mounted thereon, and a conveyor extending at right angles to said horizontal conveyor having its 50 head end adapted to be detachably supported on the said longitudinal shaft, said conveyor being provided on its head end shaft with a gear adapted to mesh with the 55 said slidable gear.
6. A marine transfer apparatus comprising, a floating structure, an inclined conveyor mounted longitudinally thereon having its tail end close to the deck of the structure and its head end elevated to above 60 a wharf level, a substantially horizontal conveyor extending outboard from the structure the head end of which is link-connected to the tail end of the inclined conveyor, a 65 shaft rotatably mounted on one side of said horizontal conveyor extending longitudinally of the same, a gear rotatably connected to said shaft slidably mounted thereon, a conveyor extending at right angles to said horizontal conveyor having its head end 70 adapted to be detachably supported on the said longitudinal shaft, said conveyor being provided with a gear adapted to mesh with the 75 said slidable gear.

Dated at Vancouver, B. C., this 17th day of March, 1921.

GEORGE ARTHUR MICKELSON.
